[57] CLAIM

The ornamental design for a display carton, substantially as shown and described.

DESCRIPTION

FIG. 1 is a right side elevational view of a display carton showing my new design, the left side being substantially a mirror image thereto;

FIG. 2 is a front elevational view taken along line 2—2 of FIG. 1;

FIG. 3 is a rear elevational view taken along line 3—3 of FIG. 1;

FIG. 4 is a bottom plan view taken along line 4—4 of FIG. 1; and

FIG. 5 is a top plan view taken along line 5—5 of FIG. 1.

FIG. 2

FIG. 1

FIG. 3

FIG. 4

FIG. 5
